UNITED STATES PATENT OFFICE

141,332

DESIGN FOR A WOVEN TEXTILE FABRIC

John Walther, New York, N. Y.

Application January 5, 1945, Serial No. 117,254

Term of patent 7 years

(Cl. D92—1)

To all whom it may concern:

Be it known that I, John Walther, a citizen of the United States of America, residing in New York, county of New York and State of New York, have invented a new, original, and ornamental Design for a Woven Textile Fabric, of which the following is a specification, reference being had to the accompanying drawing, forming part thereof,

The figure on the drawing is a plan view of a woven textile fabric showing my new design.

The characteristic feature of my design resides

in the combination on a twill mixture background of a set of four fine hairline stripes closely spaced, and an equal width set of stripes running through the background of the fabric midway between the hairline stripes, which group is composed of four broken stripes made up of two color pin dots of a novelty twist, as shown.

I claim:

The ornamental design for a woven textile fabric, substantially as shown and described.

JOHN WALThER.
